US0D1088353S

(12) **United States Design Patent** (10) **Patent No.:** **US D1,088,353 S**
(45) **Date of Patent:** **** Aug. 12, 2025**

(54) **FOLDING MIRROR**

(71) Applicant: **Huizhou Jiayao Smart Technology Co., Ltd.**, Huizhou (CN)
(72) Inventor: **Shaoyan Li**, Huizhou (CN)
(73) Assignee: **Huizhou Jiayao Smart Technology Co., Ltd.**, Huizhou (CN)
(**) Term: **15 Years**
(21) Appl. No.: **29/989,900**
(22) Filed: **Feb. 18, 2025**

Related U.S. Application Data

(62) Division of application No. 35/520,953, filed on Apr. 18, 2024 (U.S. filing date under 35 U.S.C. 384), and having an international filing date of Apr. 18, 2024.
